Des. 236,733
Patented Sept. 9, 1975

236,733

CURSOR POSITION CONTROLLER

Carl J. Clement, Mountain View, William K. English,
Portola Valley, and Fred H. Stengel, Palo Alto, Calif.,
assignors to Xerox Corporation, Stamford, Conn.

Filed Dec. 20, 1973, Ser. No. 426,848

Term of patent 14 years

Int. Cl. D13—03

U.S. Cl. D26—13 C

FIG. 1

FIG. 2

FIG. 3

FIG. 4

FIG. 5

FIG. 6

FIG. 1 is a perspective view of a cursor position controller, showing our new design;

FIG. 2 is a front elevational view of such cursor position controller;

FIG. 3 is an elevational view taken from the right side thereof;

FIG. 4 is a rear elevational view thereof;

FIG. 5 is an elevational view taken from the left side thereof; and

FIG. 6 is a top plan view thereof.

We claim:

The ornamental design for a cursor position controller, as shown.
